US00D619141S

(12) **United States Design Patent**
Chi et al.

(10) **Patent No.:** **US D619,141 S**
(45) **Date of Patent:** **** Jul. 6, 2010**

(54) **PORTION OF A DISPLAY SCREEN WITH COMPUTER USER INTERFACE**

(75) Inventors: **Liang-Yu (Tom) Chi**, San Francisco, CA (US); **Raj Gopal Prasad Kantamneni**, San Jose, CA (US); **Ashley Woodman Hall**, Menlo Park, CA (US); **Frank Henry Filippini**, Redwood City, CA (US); **Diane Wing Yip**, Foster City, CA (US)

(73) Assignee: **Yahoo! Inc.**, Sunnyvale, CA (US)

(**) Term: **14 Years**

(21) Appl. No.: **29/334,802**

(22) Filed: **Apr. 2, 2009**

(51) LOC (9) Cl. **32-00**

(52) U.S. Cl. **D14/485**

(58) Field of Classification Search **D14/485-495; 715/700-867**

See application file for complete search history.

(57) **CLAIM**

The ornamental design for a portion of a display screen with computer user interface, as shown and described.

DESCRIPTION

The sole FIGURE is a view of a portion of a display screen with computer user interface showing our new design.

The broken-lines depicting an outline of a display screen, objects in and around the computer user interface and broken-line text form no part of the claimed design.

1 Claim, 1 Drawing Sheet

SEARCH: FARM
